Patented Nov. 28, 1916.

UNITED STATES PATENT OFFICE.

RALPH H. TAYLOR, OF BUTTE, MONTANA.

MATCH-STRIKING ATTACHMENT FOR GARMENTS.

1,206,170.

Specification of Letters Patent.

Patented Nov. 28, 1916.

Application filed August 21, 1915. Serial No. 46,631.

To all whom it may concern:

Be it known that I, RALPH H. TAYLOR, a citizen of the United States, residing at Butte, in the county of Silverbow and State 5 of Montana, have invented certain new and useful Improvements in Match-Striking Attachments for Garments, of which the following is a specification.

This invention relates to match striking 10 attachments for garments and has as its object to provide an attachment which may be embodied in any ordinary coat or the like and which may be conveniently employed for the purpose of lighting matches, 15 thereby obviating the necessity of striking matches upon one's clothes by friction or lighting matches by striking them upon the pavement, building walls, woodwork, and other surfaces liable to be marred in the act 20 of striking the match and obviating also the necessity of striking the match upon one's shoe sole.

It is one aim of the invention to provide 25 an attachment of the class described which will be inconspicuous and which will not in any way detract from the appearance or neat fit of the garment.

Another aim of the invention is to provide 30 a device of this class so constructed that the striking surface may be renewed whenever desired.

In the accompanying drawings: Figure 1 35 is a perspective view illustrating the arrangement of the device within an ordinary coat and the manner in which the device would be used. Fig. 2 is a perspective view, in detail, of the attachment. Fig. 3 is a vertical sectional view therethrough. Fig. 4 is a horizontal sectional view sub- 40 substantially on the line 4—4 of Fig. 3. Fig. 5 is an enlarged horizontal sectional view of the upper transverse strip of the pocket showing the manner of securing said strip to the body of the garment.

45 Corresponding and like parts are referred to in the following description and indicated in all the views of the accompanying drawings by the same reference characters.

The device embodying the present invention 50 may be arranged within any coat, overcoat, or similar garment and in any desired location although the arrangement shown in the drawings is the one to be preferred inasmuch as it permits of more convenient striking of a match.

In the drawings the numeral 1 indicates

the facing of a coat and in carrying out the present invention a substantially rectangular opening is cut in this facing as indicated by the numeral 2 and the material of the facing 60 at the opposite sides of said opening is folded back and stitched as at 3 so as to provide hems 4 which have their edges parallel to each other and which, in a manner to be presently explained, constitute a portion of 65 the front wall of a pocket which is designed to receive sheets of emery cloth or sand paper which afford a striking surface for matches. A line of stitching 5 extending transversely of the lower end of each hem 4 serves to 70 close the bottom of the pocket above mentioned and these lines of stitching and also the lines of stitching 3 pass respectively through the lower edge portion and the lateral edge portions of a piece of cloth 75 indicated at 6, which cloth constitutes the back wall of the pocket. A strip of cloth indicated at 7 has its upper and lower edge portions folded back and stitched as shown in Fig. 3 of the drawings and this strip is 80 united by lines of stitching to the upper ends of the hems 4 and at its ends is stitched to the facing 1, the said ends being fitted through slits or incisions 11 in the said facing. The upper and lower edges of the strip 85 7 are unattached to the facing 1 and this strip therefore defines the mouth of the pocket. Any desired number of sheets of 90 emery cloth, sand-paper or other match striking material indicated by the numeral 8, are inserted within the pocket and one of these sheets will, of course, have its coated surface exposed between the adjacent edges of the hems 4 and the lower edge of the strip 7 to present the desired match striking 95 surface.

From the foregoing it will be apparent that when one of the sheets 8 becomes worn so as to be practically useless it may be withdrawn from the pocket thereby exposing the coated surface of the next adjacent sheet, and inasmuch as the sheets are relatively thin, a number may be arranged within the pocket without bulging the garment or detracting from its neat appearance 105 and fit.

In order that a supply of matches may be carried convenient to the striking device above described, a pocket indicated by the numeral 9 is provided in the facing 1 and 110 the mouth of this pocket, indicated by the numeral 10, extends transversely at the bot-

tom of the pocket which receives the striking sheets 8, the upper edge of the forward wall of the pocket 9 registering with the lower ends of the hems 4.

5 By reference to the drawings and particularly to Fig. 1, it will be observed that the match striking device and the pocket 9 are located at the left-hand side of the coat and therefore when it is desired to 10 obtain a light, a match may be conveniently removed from the pocket 9 by the right hand while the coat is held by the left hand as shown in Fig. 1, and as the match is withdrawn from the pocket its head is 15 drawn across the striking surface and is thereby ignited.

Having thus described the invention, what is claimed as new is:

1. The combination with a garment having an opening therein, of a pocket having a back wall secured to the rear surface of the cloth of which the garment is formed and extending across the opening therein, said pocket being provided with spaced 25 lateral hems comprising an open front wall, and a sheet of material removably fitted within the pocket between the hems and the back wall and having a match striking surface exposed between the adjacent edges of 30 the hems.

2. The combination with a garment, of a pocket forming a part of the garment and comprising a back wall and having an open front wall comprising spaced hems having 35 their free edges presented toward each other, a strip connecting the upper ends of the hems, the lower ends of said hems being connected with the body of the garment by

a line of stitching, and a sheet of material removably fitted within the pocket at the rear of the strip and between the hems and resting on said line of stitching, said sheet having a match striking surface presented at the opening defined by the adjacent edges of the hems and strip. 40

3. The combination with a garment, of a pocket formed directly in the body of the garment and comprising a back wall and spaced lateral hems forming an open front wall, the lower ends of said hems being 50 connected to the body of the garment by a line of stitching, a transverse strip connecting the upper ends of the hems and having its opposite ends extended through incisions in the body of the garment and secured directly to the rear face thereof, and a sheet of material removably fitted within the pocket at the rear of the strip and between the hems and resting on said line of stitching, said sheet having a match striking surface presented at the opening defined by the 55 adjacent edges of the hems and transverse strip. 45

4. The combination with a garment including a pocket having a normally open mouth, 60 of an auxiliary pocket arranged directly above the open mouth of the garment pocket and having an open front, and a sheet of match striking material removably fitted within the auxiliary pocket and having its surface exposed at said open front, the surface of the match striking material 65 being constantly in vertical alinement with the back of the garment pocket. 70

In testimony whereof I affix my signature. 75
RALPH H. TAYLOR. [L. s.]
